(57) **CLAIM**

The ornamental design for a mounting bracket, as shown and described.

DESCRIPTION

FIG. 1 is a first perspective view of the mounting bracket; FIG. 2 is a second perspective view of FIG. 1; FIG. 3 is a front elevation view of FIG. 1; FIG. 4 is a rear elevation view of FIG. 1; FIG. 5 is a left side view of FIG. 1; FIG. 6 is a right side view of FIG. 1; FIG. 7 is a top plan view of FIG. 1; FIG. 8 is a bottom plan view of FIG. 1. FIG. 9 is a first perspective view of the mounting bracket in a second embodiment; FIG. 10 is a second perspective view of FIG. 9; FIG. 11 is a front elevation view of FIG. 9; FIG. 12 is a rear elevation view of FIG. 9; FIG. 13 is a left side view of FIG. 9; FIG. 14 is a right side view of FIG. 9; FIG. 15 is a top plan view of FIG. 9; FIG. 16 is a bottom plan view of FIG. 9. FIG. 17 is a first perspective view of the mounting bracket in a third embodiment; FIG. 18 is a second perspective view of FIG. 17; FIG. 19 is a front elevation view of FIG. 17; FIG. 20 is a rear elevation view of FIG. 17; FIG. 21 is a left side view of FIG. 17; FIG. 22 is a right side view of FIG. 17; FIG. 23 is a top plan view of FIG. 17; and, FIG. 24 is a bottom plan view of FIG. 17.
